APPARATUS FOR CASTRATING ANIMALS

Louis Daroux, Manakau, Manawatu, New Zealand, assignor to Daroux Emasculators Limited, Wellington, New Zealand, a company of New Zealand

Application January 6, 1931, Serial No. 507,028
In New Zealand May 28, 1930

4 Claims. (Cl. 128—306)

The present invention relates to an improved castrating tool or instrument.

Heretofore it has been known to use an instrument which permits of bloodless castration being effected, but such instrument has many defects 5 which are overcome in my invention.

According to my invention, I provide for the first time an instrument which, while effecting bloodless operation, enables both testicles to be 10 operated upon simultaneously, which prevents the possibility of the "cord" slipping out from the crushers or pincers, and which is easily and effectively operable by one person alone.

Furthermore according to my invention I provide means which preclude under normal conditions the possibility of cutting off the blood supply to the "bag" with resultant mortification. 15

In the preferred form of the invention I provide spring tensioning means which enable a more effective and positive thrust of the crushers 20 to be obtained when the hand levers are drawn towards one another.

Other subordinate features of the invention will be hereinafter described and more particularly pointed out in the claims, but I shall now 25 describe my invention with reference to the present preferred constructional embodiment thereof illustrated in the accompanying drawings.

Figure 1 shows the instrument in the closed 30 position with the two crushers extended into their respective depressions, Figure 2 is an opposite handed view in the open position with the crushers withdrawn ready to receive the bag and testicles.

The head portion A is of solid construction having two depressions B on its inner face to receive the bag and testicles and hold the latter in their proper positions prior to the operation. The hinged block A1 is secured to the head portion A 35 by means of a hinge F and hinge pin F1. The movement of the block A1 is controlled by the spring H which is hinged at its outer end H1 to the head portion A and at its inner end H2 to the block A1. In the closed position Figure 1, it will 40 be noted that the pin F1 is off centre with a line drawn between the hinge pins H1 and H2 and conversely in the open position of the instrument Figure 2, the pin F1 is off centre in the opposite direction to the pins H1 and H2. The 45 effect of this arrangement of the pins F1, H1, and H2 is to ensure that the block A1 will automatically spring into or out of position as desired.

The block A1 is slotted to receive the slideable 50 crushers C which are held in position in the block A1 by means of slot M and pins L. The in-

ner corners C2 of the crushers C are rounded off to prevent damage to the outer skin of the bag, and are designed to engage in depressions or slots B1 in the head portion A. The object of allowing the corners C2 to engage in the slots B1 on each side of the extension O is to prevent 60 the testicle cords from slipping round the insides of the crushers C, and to force the said cords towards the centres of the crushers C.

The space shown in Figure 1 between the extension O and the spring K ensures that a certain part of the testicle bag is not so pressed as to prevent or hinder free circulation of the blood. 65

A sprink K secured to the centre of the block A1 by the preferably movable bolt J is provided 70 to press the centre of the testicle bag and force the cords outwardly into the depressions B.

A spring catch I is secured to the outer end of the block A1 and is designed to automatically engage with the outer end of head portion A to hold A and A1 in the closed position while the crushers C are being operated. Lever springs E shaped as shown to avoid interfering with the bag and testicles are provided having their outer ends pivotally secured to the head portion A 75 by bolts or pins G and their inner ends similarly secured to hand levers D by bolts or pins G1. 80

The bearings of the bolts or pins G and G1 are preferably provided with removable collar sleeves and spring washers to allow for suitable 85 tension in working joints of the levers D and springs E.

The opening movements of levers D are controlled by stops N on the springs E engaging with suitable shoulders N1 on the head portion A. 90

Hand levers D have their inner ends D1 rounded to engage with the semicircular depressions C1 on the inner faces of the crushers C.

In operation, the instrument is held open in the left hand, the opening to the right. It is 95 then pressed down on to the body of the animal with the bag and testicle cords in the opening. With the right hand the bag and testicle are placed in position between the head portion A and the hinged block A1, the latter being then 100 pressed against the portion A, using the finger and thumb of the left hand for the purpose, the closing being assisted by the spring H and automatically locked into position by the spring 105 catch I. This automatically forces the cords into the depression B. With the right hand bring right hand lever D to engage end D1 into the semicircular depression C1. Then with left hand bring the other lever D and engage it similarly. 110

Force the two levers D together and the operation is completed.

To open the instrument, press the two levers D apart. With the index finger of right hand release the spring catch I. Place levers D in position as shown in Figure 2. With left hand press hinged portion A1 inwardly and spring H will automatically force the portion A1 into the open position as shown in Figure 2. It is of course obvious that it is within the province of my invention to provide the instrument with but a single depression and a single crusher member.

It will be noticed that this operation although not cutting the bag or skin severs the blood vessels and the seminal cords, but does not prevent the blood vessels supplying blood to the "bag".

I claim:

1. An improved castrating instrument or tool comprising a head portion having two depressions on its inner face and an extension or projection therebetween, a block hinged at one end to said head portion, and forming a clamp there-with, two crusher members slidably mounted on said clamp, a flat spring mounted on the inner face of said block between said crusher members, means for detachably securing said block at its other end to the said head portion, and means operable upon the outer ends of said crusher members to force them into said depressions in said head portion.

2. An improved castrating instrument or tool as claimed in claim 1 wherein a spring secured at one end to said head portion and at its other end to the hinged end of said block snaps it into and positively but yieldingly holds it in either its open or closed position. 80

3. An improved castrating instrument or tool consisting of a head portion and a member below said head portion, one of said head portions and said member having two depressions on its inner face and an extension or projection therebetween, and the other of said head portions and said member comprising a crusher, and lever means for forcing together said crusher and said depressions, said lever means comprising two lever springs secured at one end to said head portion and at the other end to respective hand levers, said hand levers having their inner ends rounded, the rounded portions being adapted to engage in correspondingly rounded recesses in the outer ends of said crusher members. 85 90

4. An improved castrating instrument or tool consisting substantially entirely of a head portion member, another member, one of said members having at least one concave depression on its operating face, and the other of said members comprising at least one crusher having convex rounded edges, cooperating with and fitting in said depression, and pivoted lever means for forcing together said crusher and said depression-bearing member. 100 105
